UNITED STATES PATENT OFFICE.

HARTWIG MOHR, OF BROOKLYN, NEW YORK.

SWIMMING DEVICE.

Application filed December 10, 1927. Serial No. 239,235.

This invention relates to the improvement in swimming and has for its object, to render swimming much faster, more graceful and safer and less fatiguing, in short, to aid in swimming and water-treading.

A fish has fins and a tail, adapted for propelling; a seal has its hind feet converted into fin-like flappers; a steamer has its screw, a duck or goose has a web between its toes, so has a frog, in order to make swimming easier and faster. Man has not.

My invention makes of man a better swimmer, than he has ever been before.

Fig. 1 shows the device positioned for use.

Fig. 2 shows the device alone.

Fig. 3 shows the device adapted to swimming trunks.

Fig. 4 shows the device adapted to use with tights.

The device consists simply of a suitable kind of web, fastened in a suitable way between the spread legs. The web may consist of the same material, bathing caps and rubber aprons usually are made of, or may be of rubberized or oiled silk or any other flexible, waterproof fabric. The web between the spread legs will naturally have the shape of a triangle, two sides of which will have the approximate length of the legs, and the third side the length of the easy spread, say about 24 inches for a grown-up

person, between the ankles. This will not interfere with walking.

This web can be fastened by straps, preferably of the same material, around the legs; at the thigh, under the knee, around the ankle and foot. The upper part of the web is extended to a belt and fastened around the waistline, over the bathing-trunks; or it can be fastened directly to the bathing-trunks between the legs and thence with straps around the legs as above. Or the whole web can be fastened to bathing-tights, covering the entire legs.

The benefit of this device in swimming is great. By just moving the legs as in walking, a similar effect is reached, as when a fish moves the tail, a seal its flappers, a steamer the screw, etc. and swimming becomes delightfully easy, fast and not fatiguing.

I claim:

1. In a swimming-device, the flexible, single waterproof web, fastened to both legs and the body by straps and belt, substantially as set forth.

2. In a swimming-device, the flexible, single waterproof web, fastened to bathing-trunks directly and to the legs by straps, substantially as described herein.

HARTWIG MOHR.
